UNITED STATES PATENT OFFICE.

HARRIET RUTH TRACY, OF NEW BRIGHTON, NEW YORK.

DESIGN FOR A SEWING-MACHINE FRAME.

SPECIFICATION forming part of Design No. 22,544, dated June 13, 1893.

Application filed February 8, 1893. Serial No. 461,521. Term of patent 14 years.

To all whom it may concern:

Be it known that I, HARRIET RUTH TRACY, a citizen of the United States, residing at New Brighton, in the county of Richmond 5 and State of New York, have invented and produced a new and original Design for Sewing-Machine Frames, of which the following is a specification.

In the drawing, the figure represents a side elevation of a sewing machine embodying my design.

The leading feature of my design consists in the frame the upper portion of which is made in the form and configuration of a human arm and hand. The portion A of the frame, which is made in this form, is the horizontal part extending from the stationary up-

right B, to which it is attached or with which it is formed. The portion A is made to support the needle-bar, &c., of the sewing machine, and the fingers and thumb of the hand are represented as grasping the needle-bar in a life-like manner. 20

What I claim is—

The design for a sewing-machine frame, 25 substantially as shown.

In testimony whereof I have hereunto affixed my signature in the presence of two witnesses.

HARRIET RUTH TRACY.

Witnesses:

DAVID H. MEAD,
E. H. PARRY.
